CLAIM

The ornamental design for a multistage shower water filter as shown and described.

DESCRIPTION

FIG. 1 is a perspective view of a multistage shower water filter showing the new design;

FIG. 2 is a front view of the multistage shower water filter, and the rear view is identical;

FIG. 3 is a top view of the multistage shower water filter;

FIG. 4 is a left side view of the multistage shower water filter, and is a right side view is identical;

FIG. 5 is a bottom view of the multistage shower water filter;

FIG. 6 is another perspective view of the multistage shower water filter, shown mounted on a tap; and,

FIG. 7 is an exploded view of the multistage shower water filter.

The broken line showing of a multistage shower water filter is included for the purpose of illustrating portions of the article and forms no part of the claimed design.

The broken line showing of a tap in FIG. 6 is included for the purpose of illustrating environmental structure and forms no part of the claimed design.

1 Claim, 5 Drawing Sheets
